UNITED STATES PATENT OFFICE.

EMIL G. SAUER, OF RICHMOND HILL, NEW YORK, ASSIGNOR TO BIGELOW CARPET COMPANY, A CORPORATION OF MASSACHUSETTS.

DESIGN FOR A RUG.

40,800.

Specification for Design. Patented July 26, 1910.

Application filed June 6, 1910. Serial No. 565,408. Term of patent 3½ years.

To all whom it may concern:

Be it known that I, EMIL G. SAUER, a citizen of the United States, residing at Richmond Hill, Queens county, State of New York, have invented a new, original, and ornamental Design for Rugs, of which the following is a specification, reference being had to the accompanying drawing, forming part thereof.

The figure is a plan view of one of the like quarters of a rug, showing my new design.

I claim:

The ornamental design for a rug, as shown.

EMIL G. SAUER.
